UNITED STATES PATENT OFFICE.

LEO STEIN, OF ROCHESTER, NEW YORK.

DESIGN FOR A BURIAL-CASKET LID.

SPECIFICATION forming part of Design No. 19,810, dated September 10, 1889.

Application filed August 3, 1889. Serial No. 319,688. Term of patent 14 years.

To all whom it may concern:

Be it known that I, LEO STEIN, a citizen of the United States, residing at Rochester, in the county of Monroe and State of New York, 5 have invented and produced a new and original Design for Burial-Casket Lids, of which the following is a specification, reference being had to the accompanying drawings, forming part thereof.

10 Figure 1 is a plan view of a burial-casket lid showing my design, and Fig. 2 is a sectional view taken on line $x-x$, Fig. 1, illustrating the contour of the plane and beveled surfaces making up the peculiar configuration 15 of the lid, these two views being deemed necessary to fully illustrate my design.

The leading feature of my design consists in the plain upper-surfaced lid bordered by marginal beveled edges with a coincidentally-20 beveled centrally-set cross-bar dividing the lid into a head and foot section, all surrounded by an outer marginal molding or edge raised above the adjacent surface of the beveled edge of the lid extending around the lid, 25 whereby a novel and pleasing effect is presented to the eye by reason of the beveled surfaces receding from a central plain surface to a raised marginal molding or edge.

20 a represents the flat surface of the central portion of the lid. Surrounding said portion a are the beveled surfaces b , receding therefrom at an angle and blending harmoniously

therewith. Raised above the plane of the outside surface of the beveled portion b is the bordering molding or edge c . A cross-bar e 35 is arranged between the extremities of the lid, and is formed with beveled portions d , coincidently inclined with the bevel b of the lid. The cross-bar is also raised above the lid, and in addition to the pleasing effect occasioned by the plain and beveled surfaces thereof adds to the appearance by presenting to the eye the appearance of surfaces in different planes one above the other.

What I claim is—

45 The herein-described design for burial-casket lids, the same consisting of a flat surface or panel lying in a horizontal plane, a bordering-molding raised above the plane of said flat surface or panel, and beveled portions between said flat surface or panel and the bordering-molding, and also below the plane of said molding, substantially as set forth.

50 In testimony whereof I have hereunto signed my name, in the presence of two attesting witnesses, at Rochester, in the county of Monroe, in the State of New York, this 27th day of July, 1889.

LEO STEIN.
